UNITED STATES PATENT OFFICE.

ERNEST A. TESCH, OF CHICAGO, ILLINOIS.

COMBINATION DOOR BRACE AND LATCH.

Application filed July 29, 1927. Serial No. 209,325.

This invention relates to certain novel improvements in combination door braces and latches and has for its principal object the provision of an improved construction of this 5 character which will be highly efficient in use and economical in manufacture.

Among the several objects of the invention is to provide a combination door brace and latch which will function to retain the 10 door in a predetermined opened position and whereby the latch will function to automatically latch the door in closed position.

Other objects will appear hereinafter.

The invention consists in the novel combination and arrangement of parts to be hereinafter described and claimed.

The invention will be best understood by reference to the accompanying drawings, showing the preferred form of construction 20 and in which:

Fig. 1 is an inside elevational view of a door construction showing the invention associated therewith;

Fig. 2 is a sectional detail view taken substantially on line 2—2 of Fig. 1; and

Fig. 3 is a sectional detail view taken substantially on line 3—3 of Fig. 2.

Referring to the drawing, 10 indicates a door construction of a garage or other like 30 building. The door construction includes the side jambs 11 to which are hingedly connected the doors 12 through the medium of hinges 13. With these door jambs and door I associate my improved door brace and latch 35 and in the preferred form of construction the invention includes two guiding structures 14 and 15. The guiding structures each include two spaced parallel extending plates 16 and 16'. The plates are arranged in pairs and have their end portions 17 secured together 40 through the medium of spacing plates 18. These spacing plates 18 are secured to the doors 12 through the medium of screws 10 or other suitable connecting elements. The end portions 20 of the plates 16 overlap the edge 21 of the door 12' of the doors 12 and these end portions when in overlapping position abut the edges 22 of the plate 16'. The end 45 portions 20 of the plate 16 are secured to a spacing plate 23 secured to the door 12 through the medium of suitable securing elements 24 such as screws or the like. The end portions 25 of the plate 16' are secured to a spacing plate 26 secured to the door 12' 50 through the medium of screw elements 27. The plates 16 and 16' provide suitable guide-

ways 28 and slidably associated with the guiding structures are clamping structures 29. These clamping structures 29 include body sleeves 30 and projecting through these body sleeves 30 are the studs 31 formed as an integral part of heads 32. The inner end portion 33 of the studs 31 loosely project through openings 34 formed in plates 35, said plates 35 being arranged to engage the outer surface of the plates 16 and 16'. From the plates 35 the end portions 32 project through the guide ways 28 and are threaded into openings 36 formed in plates 37 disposed on the opposite side of the plates 16 and 16' in parallel relation with respect to the plates 35. The heads 32 carry suitable handle elements 38 whereby to rotate the stud 31 to clamp the plates 35 and 37 into clamping relation with respect to the plates 16 and 16' whereby to 70 releasably connect the clamping structures in a predetermined position with respect to the plates 16 and 16'.

Formed as an integral part of the body sleeve 29 are ears 39 perforated for the projection of connecting pins 40 which pivotally connect the end portions 41 of bracing rods 42 to the body sleeves 30. The opposite end portions of the bracing rods are pivotally connected as at 43 to brackets 44 secured to the jambs 11 in any approved manner.

Pivotally carried by the upper of the plate 16' is the latch bolt 45. This latch bolt 45 carries two parallel spaced plates 46 adapted to be disposed on opposite sides on the upper of the plate 16'. The outer end portion of the latch bolt 45 carries a head 47 and this head has its lower end portion beveled outwardly and downwardly as at 48 whereby when the head engages the end portion 20 of the upper of the plate 16 the latch bolt will be automatically raised to permit the head to be disposed in latching relation with respect to the upper of the plates 16, said head being of sufficient weight to cause the latch bolt to drop into latch engagement with respect to the upper of the plates 16 and 16' by gravity.

In use to open the doors, the head 32 is rotated by means of the handle elements 38 whereby to release the plates 35 and 37 from clamping engagement with the plates 16 and 16'. As the door is swung open the clamping structure will move longitudinally with respect to the guiding structures. To hold the door in the predetermined open position the heads 32 are rotated in an opposite direction

to clamp the plates 35 and 37 into clamping engagement with respect to the plates 16 and 16'.

From the description herein set forth taken 5 in connection with the accompanying drawing, it will be seen that I provide a durable structure for retaining the door in a predetermined open position and which structure includes a simple arrangement for effectively 10 latching the doors in closed position.

While I have illustrated and described the preferred form of construction for carrying my invention into effect, this is capable of variation and modification, without departing 15 from the spirit of the invention. I, therefore, do not wish to be limited to the precise details of construction set forth, but desire to avail myself of such variations and modifications as come within the scope of the appended 20 claims.

Having thus described my invention what I claim as new and desire to protect by Letters Patent is:

1. In combination, a guiding structure 25 adapted to be secured to a door and including spaced parallel members providing a guide way, a clamping structure including a stud projecting through the guideways, a plate having threaded engagement with the stud 30 and arranged on one side of said members, a plate having loose connection with the stud and arranged on the opposite side of said members in parallel relation with said first mem-

tioned plate, a body sleeve through which said stud projects, a head formed on said stud, a 35 handle carried by said head for facilitating rotation of said head to move said first and said second mentioned plate into clamping relation with said members, a bracing rod adapted for connection with the jamb to 40 which said door is hingedly supported, an ear formed on said sleeve, and means connecting said ear to one end portion of said bracing rod.

2. In combination a guiding structure 45 adapted to be secured to a door including spaced apart parallelly extending members providing a guide way, a clamping structure including plates adapted to have portions disposed on opposite sides of the portions providing said guideway so as to be slidable therealong, means for clamping said clamping plates to said plates providing said guideway, a connecting member mounted on the jamb of the door, a connecting link extending 50 between said clamping structure and said connecting member, means for pivotally connecting said connecting link to said connecting member and said clamping member, said connecting link serving to hold said door against 55 opening movement when said clamping member fastens said clamping plates against said plates providing said guideway.

In testimony whereof I affix my signature.

ERNEST A. TESCH.
